ERNST KOCHENDOERFER, OF FRANKFORT-ON-THE-MAIN, GERMANY.

PROCESS FOR MANUFACTURING NITROGEN COMPOUNDS.

1,165,358.

Specification of Letters Patent.

Patented Dec. 21, 1915.

Application filed October 31, 1912. Serial No. 728,762.

To all whom it may concern:

Be it known that I, ERNST KOCHENDOERFER, a subject of the Emperor of Germany, residing at Frankfort-on-the-Main, Germany, have invented certain new and useful Improvements in Processes for Manufacturing Nitrogen Compounds.

This invention relates to the manufacture of nitrogen compounds from the gases generated by the carbonization of distillers' wash and the like nitrogen carrying substances.

It has particular relation to the well known cyanization of certain gases, resulting from the carbonization of distillers' wash and the like, by means of over-heating; said gases have a considerable content of nitrogen, which renders them very valuable for the manufacture of nitrogen compounds such as cyanogen compounds and ammonia. There are quite a number of processes for such manufacture, but these processes are not sufficiently satisfactory because the yield of nitrogen compounds is considerably below that to be expected on theoretical calculations. The gases resulting from the carbonization of distillers' wash, hereinafter simply called "gases," consist of a great number of different organic substances, of which, however, only a part carry nitrogen as a constituent of their body; the latter organic substances forming a part of the "gases," and characterized by their content of nitrogen, may be called "nitrogen-carriers." These nitrogen-carriers mainly consist of alkylamines, resulting from the destructive distillation of betain and furthermore of a great number of complex compounds, mostly of unknown constitution, obtained by the destructive distillation of albumins and other nitrogen-containing compounds found in the distillers' wash. There is an important difference, however, in the behavior of these nitrogen-carriers, inasmuch as the alkylamines at the suitable temperature easily split up into valuable products without any formation of carbon, whereas the other nitrogen-carriers have the tendency to split up to a much greater extent, forming much carbon, which deposits in the reaction vessel, and free nitrogen gas. The transformation of these nitrogen carriers into substances available for commercial use, as for instance into hydrocyanic acid, is an endothermic process taking place at a high temperature. Just as in all

endoothermic reactions, the cyanization of the respective gases resulting from the carbonization of distillers' wash does not occur suddenly in an explosive manner, whereas on the other hand, the reaction is very much better, because of its slowness, than has usually been supposed up to the present time.

At the present state of the art it has been considered as essential for the success of the operation to have the gases come as often and as much as possible into contact with the walls of the heater. All the present processes for the cyanization of gases resulting from the carbonization of distillers' wash acknowledge this principle as a prime condition, inasmuch as the super-heater channels, with an inside lining having a rough surface for a close contact of the gases with the walls during the cyanizing process (German Patent 86913), were substituted by such channels provided with a filler (German Patent 113530), allowing a close and intimate contact of the gases with the hot filler and hence a more perfect exposure to the heat.

Contrary to the accepted standpoint, I have found that it is of great importance for the economical success of the cyanizing process to convey the necessary heat for the reaction to the gases as much as possible, by radiation from, rather than by contact with, the walls. To create the best conditions for heating the gases, as much as possible, by radiating heat, it is necessary that the gases, in passing into the reaction vessel, meet as little resistance as possible; attention must be given that the gases are not exposed to friction with the rough inside surfaces of the super-heated channels, nor should they come into contact with any obstruction such as is offered by the fillers of the old processes.

The purpose in view is conveniently obtained by my method wherein I avoid the use of fillers in the super-heater channels and conduct the gases through empty channels which are heated from the outside; a material point, however, in which my method differs from those of the prior art, consists in the fact that I provide the inside of the channels of suitable refractory material with smooth surfaces which, even at the prevailing temperature, retain their smoothness as well as their density, and are free from any tendency to become porous. The result

of this precaution is a most satisfactory yield of hydrocyanic acid as well as of ammonia, in so far as the total yield of nitrogen in the form of valuable commercial products is almost the theoretical one. It is obvious that the proportion of the yields of cyanogen and ammonia varies according to the composition of the distillers' wash.

As a raw material for the inside lining 10 of the super-heater, exhibiting the required properties, I prefer to avail myself of the properties of certain natural acid products, such as silica-silicium dioxid and zirconia-zirconium dioxid, which have a very small 15 coefficient of expansion, are amenable to vitrification and furthermore are not liable to dissolution or chemical action by the various constituents of the distillation gases.

The walls of the superheater channels consisting preferably of either vitrified silica or, of a vitrified mixture of silica and zirconia, are naturally always smooth and non-porous like glass and the distillation gases are therefore protected against the pernicious influence of contact material leading 20 to destruction of a considerable part of the gases as the high resistance of the walls prevents the formation of such contact material which in the prior art was always 25 present in the form of scales crumbling from the walls or in the form of efflorescences exuding therefrom. For the further elucidation of my invention a construction of the apparatus preferred for carrying out the 30 process is illustrated, by way of example, in the accompanying drawing.

The distillers' wash is carbonized in the fire clay retorts A and the distillation gases escape through connection pipes B into the 40 main pipe C through which they travel into a quartz-tube D surrounded by a suitable mantle E made of fire clay bricks or other suitable material. As the quartz-tube D is heated to a high temperature, flues F of 45 sufficient width are interposed between the mantle E and quartz-tube D and an inlet G and exit H is provided for the heating gases. The distillation gases are cyanized while 50 passing through the hot quartz-tube, and leave through exit I to be further treated to assume marketable form.

The process as described is particularly valuable in manufacturing nitrogen compounds, such as cyanogen compounds and 55 ammonia, and under the term "nitrogen compounds" as used in the claims, I mean to include cyanogen and ammonia, as well as other compounds coming within that broad designation.

Having described my invention, what I claim and desire to secure by Letters Patent is:

1. The process of manufacturing nitrogen compounds consisting in transforming the 65 nitrogen - carrying gases generated by the

carbonization of distillers' wash and the like nitrogen carrying substances, into a nitrogen compound by conducting said gases through unobstructed, highly heated channels, exposing the gases during their passage through said channels to heat radiating from the walls of said channels and reducing the friction of the gases with the walls of the channels by lining the inside of the latter with a smooth and non-porous glass-like material maintaining smoothness and non-porosity at the high temperature of the process. 70

2. In the process of manufacturing nitrogen compounds from the gases generated by the carbonization of distillers' wash and the like nitrogenous substances, the transformation of the nitrogen-carrying gases into a nitrogen compound by superheating the gases within the walls of highly heated 85 channels, consisting of smooth vitrified acid material resistant to the constituents of the gases.

3. In the process of manufacturing nitrogen compounds from the gases generated by the carbonization of distillers' wash and the like nitrogenous substances, the transformation of the nitrogen-carrying gases into a nitrogen compound by superheating the 90 gases within walls having glass-like smoothness. 95

4. In the process of manufacturing nitrogen compounds from the gases generated by the carbonization of distillers' wash and the like nitrogenous substances, the transformation of the nitrogen-carrying gases into a nitrogen compound by superheating the 100 gases within smooth walls having glass-like non-porosity.

5. In the process of manufacturing nitrogen compounds from the gases generated by the carbonization of distillers' wash and the like nitrogenous substances, the transformation of the nitrogen-carrying gases into a nitrogen compound by superheating the 105 gases within walls made of material retaining a glass-like smoothness at the high temperature necessary for carrying out the process. 110

6. In the process of manufacturing nitrogen compounds from the gases generated by the carbonization of distillers' wash and the like nitrogenous substances, the transformation of the nitrogen-carrying gases into a nitrogen compound by superheating the 115 gases within smooth walls made of material retaining a glass-like non-porosity at the high temperature necessary for carrying out the process. 120

7. In the process of manufacturing nitrogen compounds from the gases generated by the carbonization of distillers' wash and the like nitrogenous substances, the transformation of the nitrogen-carrying gases into a nitrogen compound by superheating the 125 130

gases within walls of superheater-channels smooth inside and made of material free from any tendency to become porous at the high temperature necessary for carrying out 5 the process.

8. In the process of manufacturing nitrogen compounds from the gases generated by the carbonization of distillers' wash and the like nitrogenous substances, the transformation of the nitrogen-carrying gases into a nitrogen compound by superheating the gases within smooth non-porous walls of superheater channels consisting of vitrified oxids.
- 10 9. In the process of manufacturing nitrogen compounds from the gases generated by the carbonization of distillers' wash and the like nitrogenous substances, the transformation of the nitrogen-carrying gases into a 20 nitrogen compound by superheating the

gases within smooth non-porous walls of superheater channels consisting of vitrified oxids comprising zirconia.

10. In the process of manufacturing nitrogen compounds from the gases generated by 25 the carbonization of distillers' wash and the like nitrogenous substances, the transformation of the nitrogen-carrying gases into a nitrogen compound by superheating the gases within smooth non-porous walls of superheater channels consisting of vitrified 30 oxids comprising silicon dioxid.

In testimony whereof I have signed this specification in the presence of two subscribing witnesses.
